STICK-HOCKEY GAME BOARD

James W. Parnell, Jr., Charlotte, N.C.

Application May 11, 1959, Serial No. 55,856

Term of patent 14 years

(Cl. D34—5)

The dominant features of the design reside in the portions shown in full lines.

I claim:

The ornamental design for a stick-hockey game board, substantially as shown and described.
